UNITED STATES PATENT OFFICE.

SIMON C. COLLIN, OF PHILADELPHIA, PENNSYLVANIA, ASSIGNOR OF ONE-HALF TO WILLIAM WHITE, JR., OF PITTSBURG, PENNSYLVANIA.

FLUE CONNECTION FOR FURNACES.

SPECIFICATION forming part of Letters Patent No. 692,240, dated February 4, 1902.

Application filed August 9, 1901. Serial No. 71,477. (No model.)

To all whom it may concern:

Be it known that I, SIMON C. COLLIN, a citizen of the United States, residing at Philadelphia, in the county of Philadelphia and State 5 of Pennsylvania, have invented certain new and useful Improvements in Flue Connections for Furnaces; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to an improved flue connection arranged to be interposed between an air or gas supply pipe and a furnace-inlet in a manner to permit ready disconnection when desired, the flue connection, which is 20 preferably in the form of an elbow, being designed for use more especially with furnaces of the open-hearth tilting type, whereby the tilting operation is greatly facilitated.

The invention also contemplates a flue connection which is protected against the action 25 of heat and which in both its sealing and unsealing adjustments has an air or gas tight joint with the supply-pipe.

The nature of the invention will be readily 30 comprehended, reference being had to the following detailed description and to the accompanying drawings, in which the invention is illustrated in its preferred form, although I desire it understood that many 35 changes in construction may be made without departing from the spirit of the invention.

In the drawings, Figure 1 is a vertical central sectional view of a flue connection embodying my invention, the connection being 40 shown as sealing the opening of a furnace and dotted lines indicating the unsealing position of the connection. Fig. 2 is a side elevation of the flue connection. Fig. 3 is a 45 front elevation of a series of flue connections, two of which are for air and the other for gas.

Referring to the drawings by letter, A denotes the air or gas supply pipe, at the upper end of which is a well B, formed by an outer 50 annular wall A' and an inner concentric wall

A², having a height preferably greater than that of the outer wall.

C designates the furnace, which in the drawings is of the open-hearth tilting type and is provided with openings for air and for gas, 55 the opening c (shown in Fig. 1) being for the latter fluid.

D is the flue connection, preferably of elbow form, having an aperture corresponding to the size of the furnace-opening c and the supply- 60 pipe opening. At its upper end is an annular chamber E for water, the outer side of the chamber seating in practice against the furnace-wall about the furnace-opening.

E' is an annular chamber at the lower end 65 of the elbow in communication with a chamber E², which partly or wholly surrounds the elbow. Water is supplied to the chambers E E' E² by a pipe f, and g g' are preferably valved drain-pipes, which lead from the chambers E E' into the well B. In the well is an overflow-pipe h to maintain a predetermined water-level. Depending from the lower end 70 of the elbow is a flange d. The elbows are each supported by flanged wheels I I' at each side thereof, which engage parallel track-rails J J, preferably secured to or forming a part of the outer wall A' on the supply-pipe A. Fixed to an end of the axle i of the wheels I 75 is a lever K.

In operation water is continuously admitted to the water-chambers and passes thereto from through the drain-pipes into the well, from whence it is carried off through the overflow-pipe. The flange d, depending from 85 the lower end of the elbow, extends into the well B below the level of the water therein, providing between the elbow and supply-pipe a water-seal connection, whereby escape of gas or air is effectually prevented. The elbow is, through its wheel and rail support, movable to bring its upper end in seating position against the furnace-wall about its opening to establish a connection between the supply-pipe and furnace-opening, as shown 90 in full lines in Fig. 1, and is also movable to carry its upper end away from the furnace-opening to permit tilting of the furnace and also to cut off from the furnace the air or gas supply, the retracted position of the elbow 95 100

being indicated by dotted lines in said figure. Said movements of the elbow may be accomplished in a variety of ways, but preferably by moving the lever K to rotate the supporting and traction wheels I.

In both of the stated positions of the elbow and during the movement of the latter the flange d is submerged in the water contained in the well B, and therefore the water-seal connection between the elbow and supply-pipe is at all times maintained and leakage of air or gas prevented.

The elbow is preferably constructed of cast-iron lined with refractory material, such as fire-brick. Preferably three elbows are provided at each end of the furnace, two of which are for air and the other or central elbow for gas. When natural gas or coke-oven gas is used, the gas connection is made at the nozzle l. A ring m is provided at the top of the elbow to facilitate the handling of the latter in assemblage and repairs.

It will be understood that in the movement of the elbows the drain-pipes trail in the water contained in the well and that the water-pipe f has preferably a flexible connection with the water-supply.

The provision of the water-jackets, located especially at the points shown and described, greatly increases the durability and effectiveness of the elbow and materially reduces the labor and expense attending the operation of open-hearth tilting and other types of furnaces.

35 I claim as my invention—

1. The combination of a supply-pipe, a water-containing receptacle around the upper end of the supply-pipe, an elbow having a surrounding water-jacket and provided at its 40 lower end with an annular flange depending into said water-containing receptacle to provide a water-sealed connection between the

supply-pipe and elbow, means for supporting the elbow to permit lateral movement thereof to and from the furnace-opening, a water-supply pipe leading to the water-jacket, a drain-pipe connection between the water jacket and receptacle, and an overflow-pipe leading from the receptacle.

2. The combination of a supply-pipe, a water-containing receptacle around the upper end of the supply-pipe, an elbow having an upper water-jacketed end adapted to be seated around a furnace-opening and having a lower water-jacketed end and provided with an annular flange depending into the receptacle to provide a water-sealed connection between the supply-pipe and elbow, a water-supply pipe leading to both water-jackets, drain-pipes leading from said jackets into the receptacle, an overflow-pipe leading from the receptacle, and means for supporting the elbow to permit lateral movement thereof to and from the furnace-opening.

3. The combination of a supply-pipe, a water-containing receptacle around the upper end of the supply-pipe, a water-jacketed elbow provided with an annular flange depending from its lower end into the receptacle to provide a water-sealed connection between the supply-pipe and elbow, a water-supply pipe leading to the water-jacket, a valved drain-pipe leading from the water-jacket into the receptacle, a drain-pipe leading from the receptacle, wheels on the elbow supported by track-rails, and a lever connected with the wheel-axle to move the elbow to and from the furnace-opening.

In testimony whereof I affix my signature in presence of two witnesses.

SIMON C. COLLIN.
